BLOW-DOWN SYSTEM FOR BOILERS

Harry H. Weeden, Drexel Hill, Pa.

Application September 12, 1935, Serial No. 40,250

1 Claim. (Cl. 122—379)

(Granted under the act of March 3, 1883, as
amended April 30, 1928; 370 O. G. 757)

The invention relates broadly to a system for blowing-down boilers and more particularly to a safety indication therefor.

In the present type of boilers, possibility of the operator being scalded by coming into contact with water and live steam under high pressure when blowing-down a boiler is ever present. Many of the boilers of the present type are designed to introduce the blow directly into a drain, and when this method is used the operator has no means of determining when a complete blow-down has been effected because no provision is made to indicate whether or not the water has passed through and steam is following. Other boilers are designed to allow the water to flow first into a funnel and then to a drain. This method is likewise unsafe to the operator because the drain may become clogged causing the water to rise in the funnel and overflow. A further method employed in other boiler designs is to fully enclose the top of the funnel. This method does not eliminate the element of danger to an operator, because, should the drain or sewer become clogged, a pressure will build up in the funnel sufficient to cause its destruction. Even though the funnel may be of sufficient strength to withstand the pressure imposed upon it, the uncertainty of knowing whether a blow-down is complete and whether all parts have a free and clear passage, is present. The entire operation is invisible, leaving a certain amount of "guess work" to the operator, which ultimately may lead to an explosion in the blow-down system.

One of the objects of the present invention is to overcome the above referred to disadvantages by providing visible or otherwise indication whereby an operator may be informed at all times of the actual condition in blowing-down a boiler.

Another object of the invention is the provision of a receptacle for receiving the water and steam when a boiler blow-down system is exhausted, said receptacle being entirely enclosed to avoid any hazard to the operator.

Another object of the invention is to provide means permitting expansion of the blow-down pipes due to increase in pressure in the blow-down chamber.

With these and other objects in view, as well as other advantages which may be incident to the use of the improvements, the invention consists of the parts and combinations thereof hereinafter set forth and claimed, with the understanding that the several necessary elements constituting the same may be varied in proportion and arrangement without departing from the

nature and scope of the invention as defined in the appended claim.

In order to make the invention more clearly understood there are shown in the accompanying drawing, means for carrying the invention into practical effect, without limiting the improvements in their useful application to the particular construction, which, for purpose of explanation, have been made the subject of illustration.

In the accompanying drawing:

Fig. 1 is a side elevational view of a portion of a blow-down system of a boiler;

Fig. 2 is a sectional view on the line 2—2 of Fig. 1, and

Fig. 3 is a plan view of the structure shown in Fig. 1.

Referring to the drawing, an apparatus constructed in accordance with the invention is shown as comprising receptacle or bowl 4 having a body member 21 and a top member 16, secured together by suitable fastening elements 19 passing through flanges 17 and 18 provided on the cover and body members respectively, and an interposed packing gasket 20. The lower portion of the body member 21 is provided with an outlet opening communicating with a drain through a pipe 5.

The apparatus also includes a gauge glass A, a sediment bowl B and a feed water regulator C, each connected to the bowl by pipe lines 2—3, 30 11—9, and 12—10, respectively, the flow through the lines being controlled by standard gate valves 1. The pipes 3, 9 and 10 extend downwardly into the receptacle through packing glands 6, 13 and 14, respectively, in which they are free to slide to accommodate expansion and contraction due to changes in the temperature of the pipes. The lower ends of the pipes 3, 9 and 10 are formed with flared ends 15 in order to prevent their displacement from the glands 6, 13 and 14. A pressure gauge 8 is mounted on the exterior of the receptacle 4 whereby fluctuations in pressure in the bowl are indicated. A normally open check valve 7 is also mounted on the rear of the receptacle to provide a vent for steam entering the bowl in blowing-down a boiler.

When it is desired to blow-down a boiler, one or more of the valves 1 are opened, permitting water from the gauge glass A, for example, to flow at boiler pressure through pipes 2 and 3 into the bowl or receptacle 4, whence it will pass through the drain 5. During the blow-down operation, a small amount of steam will rise from the water finding its way to the atmosphere through check valve 7.

As long as a small amount of steam is escaping through the check valve the operator knows that the system is functioning properly, but when a large amount of steam escapes, he knows that a complete blow-down has been effected. Steam will be visible to the operator as long as the water is carried off through the drain.

However, should the drain become clogged, pressure will build up in the receptacle closing the valve 7 shutting off the escaping steam, and at the same time this pressure will be indicated on the pressure gauge 8. The escaping steam causes an audible and visible indication, which if thus interrupted warns the operator of approaching danger in time for him to protect himself and/or the blow-down system by closing the valve or valves 1.

As the gauge glass is usually placed some distance away from the receptacle 4, some expansion may be expected in the pipe lines due to the heat from the water passing therethrough. This expansion may take place in the present construction without causing damage to the elements of the blow-down system for the reason that the portions 3, 9 and 10 of the pipe lines are free to move through the packing tubes 6, 13 and 14. Were it not for the bell-shaped or flared end 15 of the pipe 3, there might be a possibility of its being forced through the gland 13 by the increased pressure, thus endangering the operator.

Although I have described the operation of my invention in connection with the gauge water glass of a boiler, it is to be understood that when blowing-down the sediment bowl or feed-water regulator, the operation is the same.

It will be understood further that the above description and accompanying drawing comprehend only the general and preferred embodiment of my invention and that various changes in details of construction, proportion and arrangement of parts, may be made within the scope of the appended claim without sacrificing any of the advantages of my invention.

The invention described herein may be manufactured and used by or for the Government of the United States of America for governmental purposes without the payment of any royalty thereon or therefor.

What I claim is:

Apparatus of the character described comprising a receptacle having an inlet for communication with a blow-down pipe of a steam boiler and an outlet for communication with a drain, said blow-down pipe having a sliding connection 20 with said receptacle to accommodate expansion and contraction of said pipe with changes in the temperature thereof and said outlet being of greater cross-sectional area than said inlet to prevent pressure from developing in said receptacle under normal conditions; a normally open check valve communicating with said receptacle for permitting the escape of steam to indicate when a blowing-down operation is completed and adapted to close under fluid pressure in said receptacle due to an obstruction in said drain; and means for indicating the fluid pressure in said receptacle.
